ERNEST B. GREGOR, OF DETROIT, MICHIGAN.

CONVERTIBLE PIANO-BENCH.

1,119,275.

Specification of Letters Patent.

Patented Dec. 1, 1914.

Application filed May 5, 1913. Serial No. 765,479.

To all whom it may concern:

Be it known that I, ERNEST B. GREGOR, a citizen of the United States, residing at Detroit, county of Wayne, State of Michigan, have invented a certain new and useful Improvement in Convertible Piano-Benches, and declare the following to be a full, clear, and exact description of the same, such as will enable others skilled in the art to which it pertains to make and use the same, reference being had to the accompanying drawings, which form a part of this specification.

This invention relates to convertible piano benches adjustable for use in connection with a piano or a pneumatic piano player, the seat portion of the bench being level as is desirable when used in playing a piano, and which is readily raised to a position inclined to the horizontal when used in pumping the piano player.

An object of the invention is a simple and comparatively inexpensive bench quickly and easily adjusted for use under either of the conditions mentioned and that is automatic in action requiring no adjusting screws or the setting of any part to hold the seat in either position.

The invention further consists in the novel arrangement of parts whereby the weight of the seat portion aids in the raising or lowering of the connected parts.

The means by which these and further objects and novelties of the invention are accomplished are hereinafter more fully described and claimed and shown in the accompanying drawings in which—

Figure 1 is a perspective view of a portion of a piano bench showing the appearance of the bench when the seat portion is level and in its lowermost position. Fig. 2 is a similar view showing the appearance of the bench when the seat is raised and in its inclined position. Fig. 3 is a perspective view of part of the bench showing the seat board being operated to actuate a latch whereby the returning of the seat board toward its original position raises the adjustable frame. Fig. 4 is a similar view showing the position of parts after the frame has been raised. Fig. 5 is a detail showing the latch and the actuating member to which it is pivoted in the positions assumed thereby when the seat board is raised. Fig. 6 is a similar view showing the parts in the position assumed

during the raising of the auxiliary frame. Fig. 7, is a similar view showing the parts in position assumed when the cover and auxiliary frame are in their lowermost position. Fig. 8 is a detail showing the hinge device connecting the auxiliary and the main frames.

Similar characters refer to similar parts throughout the drawings and specification.

As shown more particularly in Figs. 1 to 4 inclusive, the bench consists of a main box-like frame portion 1 supported in any approved manner as by the legs 2, 2, etc. As shown more clearly in Figs. 3 and 4, an auxiliary frame 3 is provided, attached to and forming part of which is a comparatively wide molding strip 4 in telescope engagement with the main frame 1, as herein-after shown. The seat board 5 is hinged to the auxiliary frame 3 and as shown more clearly in Fig. 4, the auxiliary frame 3 is hinged to the main frame 1 by a peculiar hinge arrangement near each end of the bench, the arrangement being such that if force be applied to one side of the auxiliary frame tending to raise it the frame will rise upon all sides alike.

Preferably near the center of the bench and hinged to the seat board or cover is a slotted bar 6 to the lower end of which is pivoted the latch 7. A pin 8, secured in a cross-bar 80 of the bench engages in the slot 9 of the bar 6, and also slidably supported on the cross-bar is a plate 10 supported in position by the pins 11 and 12 which engage in the slots 13 and 14 of the plate 10. The plate is also provided with up-standing lugs 15 and 16 which are a sufficient distance apart to allow the widest part of the bar 6 to pass therebetween as it is moved up or down on the pin 8 by actuation of the seat board 5. The bar 6 is provided with a projecting portion 17 upon one edge thereof near the lower end which engages against the lug 15 on the plate 10 as the bar 6 is drawn upward from the position shown in Fig. 7 to the position shown in Fig. 5, and in thus drawing the bar between the lugs the projection 17 slides the plate 10 to the right of the Fig. 7 bringing the lug 16 in position to be engaged by the projection 18 on the latch whereupon the latch assumes the position shown in Fig. 3, with the hook part thereof in position to engage the pin 8 when the bar is moved downward by movement of the seat board. 110

The engagement of the pin 8 by the latch stops the downward movement of the bar 6, and the seat board then swivels on the hinge point 90, and as the forward edge of 5 the seat is hinged to the auxiliary frame at 19 as shown in Figs. 3 and 4 the swiveling of the seat board upon the point 90 raises the auxiliary frame 3 as the seat is swung downward toward its original position as 13 shown in Fig. 6.

As heretofore stated the auxiliary frame 3 is hinged to the main frame 1 at each end of the bench and this hinge is preferably of the form shown more particularly in Figs. 15 4 and 8 in which the member 20 is hinged at each end to the auxiliary frame 3, and is also pivoted to the companion hinge member 21, which in turn is pivoted to the main frame 1, the upper leaf 20 being somewhat 20 wider than the lower leaf 21, and the leaf 21 is provided with the standards 22 and 23 preferably formed integrally with the hinged member 21. The standard 22 is of some- 25 what greater length than the standard 23 and when the hinge is extended and the auxiliary frame in its uppermost position the bars or standards 22 and 23 assume a perpendicular position and form a support for the seat board being of sufficient rigidity 30 for such purpose, and the standard 22 being of greater length than the standard 23, the seat board, in this position of parts, remains in an inclined position. This is desirable for the reason that the bench when in the 35 raised position shown is to be used with a pneumatic piano player which the operator pumps by means of the feet, and the inclined position of the seat board prevents the operator from sliding backward by reason of pushing against the operating pedals. 40 As may be seen more clearly in Fig. 6, the molding strip 4 when the auxiliary frame is raised serves to cover the space between the auxiliary frame and the main frame so that 45 the bench presents a neat appearance and the interior mechanism is not exposed to view.

To return the auxiliary frame and seat cover to its lowermost position as shown in 50 Fig. 7 from the raised position as shown in Fig. 6, the seat board is again raised to the position as shown by dotted lines in Fig. 6, and in so doing the projecting portion 24 of the latch 7 engages the lug 15 on the plate 55 10 which forces the hook portion of the latch to the right and out of possibility of engagement with the pin 8 during the downward movement of the bar 6 when seat board is turned to the right toward its original 60 position. As the hook is now free from engagement with the pin the weight of the auxiliary frame and seat board will cause them to naturally fall to the position shown in Fig. 7. As the auxiliary frame moves to- 65 ward the main frame the hinged members

20 and 21 fold together with the standards 22 and 23 also move out of position, and in order that they may move a sufficient distance to be below the position to be finally assumed by the seat board, the hinge member 20 is made somewhat wider than the hinge member 21. As is shown in Fig. 8, the point of pivoting the member 20 to the member 21 is as near the point of pivoting the member 21 to the 75 main frame as is feasible in order that a quick downward movement of the standards may be produced under the described action. As the parts come to rest in their lowermost position the latch 7 and the supporting bar 6 assume the position shown in Fig. 7, and the bar 10 on the cross-bar is moved to the right as far as is possible so that upon the next upward movement of the latch the projection 18 will engage the lug 16 on the plate as shown in Fig. 5 and force the hook part of the latch over the pin 8.

In the construction shown it is to be noted that the weight of the movable parts is utilized both in the raising and the lowering of the auxiliary frame, the weight of the seat board itself being utilized in raising the auxiliary frame as it swings on the pivot 90 and, as before described, the weight of both the frame and seat board causing the same to naturally fall to their lowest position upon proper actuation of the latch member.

From the foregoing description it may be seen that the device is both simple and inexpensive, and that the operation to raise and lower the auxiliary frame is most readily performed.

Having thus briefly described my invention, what I claim and desire to secure by Letters Patent of the United States is—

1. A piano bench comprising a main box-like frame, an auxiliary frame, a seat board forming a cover for the bench and hinged to said auxiliary frame, and means actuated by swinging the cover whereby the auxiliary frame may be raised or lowered by movement of the seat board about the hinge points.

2. A convertible piano bench comprising a main box-like frame, an auxiliary frame in telescopic relation therewith, a seat board forming a cover for the bench and hinged to the auxiliary frame, and means whereby the auxiliary frame may be raised or lowered by movement of the seat board about the hinge points.

3. A convertible piano bench comprising a main box-like frame, an open auxiliary frame in telescopic relation therewith, extensible hinges connecting the main and auxiliary frames, a seat board forming a cover for the bench and hinged to the auxiliary frame, and means whereby the auxiliary

frame may be raised or lowered by movement of the seat board about the hinge points.

4. A convertible piano bench comprising a main box-like frame, an open auxiliary frame, extensible hinges connecting the main and auxiliary frame, a seat board forming a cover for the bench and hinged to the auxiliary frame, means whereby by the auxiliary frame may be raised or lowered by movement of the seat board about the hinge points, and standards in operative relation with the extensible hinges whereby when the auxiliary frame is raised and said hinges extended the standards are brought to position to support the seat board and relieve the auxiliary frame of its weight.

5. A convertible piano bench comprising a main box-like frame, an open auxiliary frame in telescopic relation therewith, a seat board forming a cover for the bench and hinged to the auxiliary frame, a latch carrying member pivoted to the seat board, a guide on the main frame for said latch carrying member, a latch carried by said member, means on the main frame operated by a movement of the latch carrying member adapted to throw the latch into and out of operative position whereby initial movement of the seat board about the hinge points sets the latch and a succeeding movement of the seat board raises the auxiliary frame and a following movement of the seat board disengages the latch and lowers the auxiliary frame substantially as described.

6. A convertible piano bench comprising a main box-like frame, an auxiliary frame

in telescopic relation therewith, a seat board forming a cover for the bench and hinged to the auxiliary frame, and means whereby the auxiliary frame may be raised or lowered by movement of the seat board about the hinge points; said means comprising a slotted latch carrying member pivoted to the seat board, a pin or lug on the main frame passing through said slot and forming a guide for the movement of the latch carrying member, a latch pivoted to said member and adapted to engage the pin, a slidable plate mounted on the main frame and having lugs thereon, the latch carrying member being so formed and positioned as to slide the plate when moved by reason of its engagement with the lugs on the plate when moved up or down on the pin, said latch member having projecting portions adapted to engage one or the other of said lugs when the latch carrying member is raised whereby it may engage or be disengaged from said pin substantially as described.

7. A piano bench comprising a main box like frame, an open auxiliary frame, one of said frames being inclosed by the other, a seat-board forming a cover for the bench and hinged to said auxiliary frame, and means whereby the auxiliary frame may be raised or lowered by movement of the seat-board about the hinge points.

In testimony whereof, I sign this specification in the presence of two witnesses.

ERNEST B. GREGOR.
